Attorney

UNITED STATES PATENT OFFICE.

MAYME HARRIS, OF PALISADES, COLORADO.

OVEN-RACK.

1,168,200.

Specification of Letters Patent. Patented Jan. 11, 1916.

Application filed May 14, 1915. Serial No. 28,137.

To all whom it may concern:

Be it known that I, MAYME HARRIS, a citizen of the United States of America, residing in Palisades, in the county of Garfield, State of Colorado, have invented a new and useful improvement in OVEN-RACKS, which improvement consists in a rack having a plurality of adjustable legs, a supportable base, a supportable top, and a supportable oven-rack.

This invention relates to an improvement in an oven-rack having a supportable top, a supportable base, and a supportable oven-rack.

The improvement consists in a supportable oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

the rack and each guide bar comprises telescopic sections 12 and 13, the section 12 sliding into and out of the section 13. Formed

in the side of the supportable oven-rack is a slot 14.

The supportable oven-rack has a supportable oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

This invention relates to an improvement in an oven-rack having a supportable top, a supportable base, and a supportable oven-rack.

precise details of construction herein described and delineated, as modification and variation may be made within the scope of the claims without departing from the spirit 5 of the invention.

I claim:

1. An oven rack comprising transverse bars each formed of telescopic sections whereby the width of the rack may be varied, longitudinal bars secured to said transverse bars and each formed of telescopic sections whereby the length of the rack may be varied, the sections of one of said longitudinal bars being formed with interchangeable 15 alining openings, and a pin adapted to be passed through the alining openings to hold the sections of the longitudinal bars in adjusted position.
2. An oven rack comprising transverse bars each formed of telescopic sections whereby the width of the rack may be varied, longitudinal bars secured to said transverse bars and each formed of telescopic sections whereby the length of the rack may 20

be varied, and runners carried by the ends 25 of said transverse bars and holding the transverse and longitudinal bars spaced apart from the bottom wall of the oven.

3. An oven rack comprising transverse bars each formed of telescopic sections 30 whereby the width of the rack may be varied, longitudinal bars secured to said transverse bars and each formed of telescopic sections whereby the length of the rack may be varied, runners carried by the ends of 35 said transverse bars and holding the transverse and longitudinal bars spaced apart from the bottom wall of the oven, each runner comprising telescopic sections, and lugs formed on the inner side of each runner 40 and engaging in the adjacent ends of the respective transverse bars.

In testimony whereof I affix my signature, in presence of two witnesses.

MAYME HARRIS.

Witnesses:

R. H. BANCROFT,
DAVID F. STRAIN.
